(57) **ABSTRACT**

A new and distinct cultivar of Lily plant named 'Tiny Orange Sensation', characterized by its small to medium plant size; vigorous growth habit; freely flowering habit; orange-colored tepals with red purple-colored speckling towards the center of the flower; and good postproduction longevity.

1 Drawing Sheet

1

Botanical designation: *Lilium hybrida*.
Cultivar denomination: 'Tiny Orange Sensation'.

BACKGROUND OF THE INVENTION

The present Invention relates to a new and distinct cultivar of Asiatic Hybrid Lily plant, botanically known as *Lilium hybrida*, and hereinafter referred to by the name 'Tiny Orange Sensation'.

The new Asiatic Hybrid Lily plant is a product of a planned breeding program conducted by the Inventor in 't Zand, The Netherlands. The objective of the breeding program was to develop new potted Asiatic Hybrid Lily plants with erect flowers, attractive flower coloration and good postproduction longevity.

The new Asiatic Hybrid Lily plant originated from a cross-pollination in 1995 of *Lilium hybrida* 'Tiny Sensation', disclosed in U.S. Plant Pat. No. 17,617, as the female, or seed, parent with an unnamed proprietary selection of *Lilium hybrida*, not patented, as the male, or pollen, parent. The new Asiatic Hybrid Lily plant was discovered and selected by the Inventor as a flowering plant from within the resultant progeny of the cross-pollination in a controlled greenhouse environment in 't Zand, The Netherlands in May, 1999.

Asexual reproduction of the new Asiatic Hybrid Lily plant by bulb scales in a controlled greenhouse environment in 't Zand, The Netherlands since November, 1999, has shown that the unique features of this new Asiatic Hybrid Lily plant are stable and reproduced true to type in successive generations.

SUMMARY OF THE INVENTION

Plants of the new Asiatic Hybrid Lily have not been observed under all possible environmental conditions. The phenotype may vary somewhat with variations in environment such as temperature and light intensity without, however, any variance in genotype.

The following traits have been repeatedly observed and are determined to be the unique characteristics of 'Tiny Orange

2

'Sensation'. These characteristics in combination distinguish 'Tiny Orange Sensation' as a new and distinct cultivar of Asiatic Hybrid Lily plant:

1. Small to medium plant size.
2. Vigorous growth habit.
3. Freely flowering habit.
4. Orange-colored tepals with red purple-colored speckling towards the center of the flower.
5. Good postproduction longevity.

Plants of the new Asiatic Hybrid Lily differ from plants of the female parent, 'Tiny Sensation' in the following characteristics:

1. Plants of the new Asiatic Hybrid Lily are taller than plants of 'Tiny Sensation'.
2. Plants of the new Asiatic Hybrid Lily have stronger pedicels than plants of 'Tiny Sensation'.
3. Plants of the new Asiatic Hybrid Lily and 'Tiny Sensation' differ in flower color as flowers of plants of 'Tiny Sensation' have less speckling.

Plants of the new Asiatic Hybrid Lily differ from plants of the male parent selection primarily in plant height as plants of the new Asiatic Hybrid Lily are taller than plants of the male parent selection.

Plants of the new Asiatic Hybrid Lily can be compared to plants of Asiatic Hybrid Lily 'Orange Pixie', disclosed in U.S. Plant Pat. No. 5,792. Plants of the new Asiatic Hybrid Lily differ from plants of 'Orange Pixie' in the following characteristics:

1. Plants of the new Asiatic Hybrid Lily have broader leaves than plants of 'Orange Pixie'.
2. Plants of the new Asiatic Hybrid Lily have larger and flatter flowers than plants of 'Orange Pixie'.

DESCRIPTION OF THE PHOTOGRAPH

The accompanying colored photograph illustrates the overall appearance of the new Asiatic Hybrid Lily plant, showing the colors as true as it is reasonably possible to obtain in colored reproductions of this type. Colors in the photograph

may differ slightly from the color values cited in the detailed botanical description which accurately describe the colors of the new Asiatic Hybrid Lily plant. The photograph comprises a side perspective view of a typical flowering plant of 'Tiny Orange Sensation' grown in a container.

5

DETAILED BOTANICAL DESCRIPTION

In the following description, color references are made to The Royal Horticultural Society Colour Chart, 2001 Edition, except where general terms of ordinary dictionary significance are used. The aforementioned photograph and following observations and measurements describe plants that had been growing for about five months in 't Zand, The Netherlands under commercial practice in a glass-covered greenhouse. Plants were grown at a minimum temperature of about 15° C. and the average daylength was about 14 hours. Measurements and numerical values represent averages for typical flowering plants. The photograph and the description were taken during the winter.

10

Botanical classification: *Lilium hybrida* 'Tiny Orange Sensation'.

15

Parentage:

Female, or seed, parent.—*Lilium hybrida* 'Tiny Sensation', disclosed in U.S. Plant Pat. No. 17,617.

20

Male, or pollen, parent.—Unnamed proprietary selection of *Lilium hybrida*, not patented.

Plant description:

Plant form/growth habit.—Upright flowering plant; single erect flowering stem with a terminal cluster of flowers; small to medium plant size.

25

Growth habit.—Vigorous.

Plant height, soil level to top of flowers.—About 36.5 cm.

30

Plant diameter.—About 20 cm.

35

Flowering stems.—Diameter: About 2 cm to 2.5 cm. Internode length: About 1 cm to 2 cm. Strength: Strong. Texture: Smooth, glabrous. Color: Close to 143B.

Leaves.—Arrangement: Alternate; simple; sessile. 40 Quantity of leaves per plant: About 118. Length, lower leaves: About 8 cm. Width, lower leaves: About 1 cm. Length, upper leaves: About 6.5 cm. Width, upper leaves: About 1 cm. Shape: Lanceolate. Apex: Acute. Base: Decurrent. Margin: Entire. Texture, upper and lower surfaces: Glabrous, smooth; leathery. Venation pattern: Parallel. Color: Developing and fully expanded leaves, upper surface: Close to 137A; venation, close to 137A. Developing and fully expanded leaves, lower surface: Close to 137C; venation, close to 137C.

45

Bulbs.—Diameter: About 10 cm to 20 cm. Texture: Smooth. Color: Close to 155D.

50

Flower description:

Flowering habit.—Terminal single flowers arranged on a raceme on long, mostly erect and strong flowering stems. Flowers face mostly upright.

55

Fragrance.—Slightly fragrant.

Natural flowering season.—Plants flower in June and July in The Netherlands. Plants can be flowered year-round in the greenhouse and forced to bloom about 55 days after planting bulbs.

Flower longevity on the plant.—About 10 to 15 days; tepals not persistent; gynoecium persistent.

Flower buds.—Length: About 8.5 cm. Diameter: About 2.5 cm. Circumference: About 7.5 cm. Shape: Lanceolate. Texture: Slightly pubescent. Color: Close to 23B brushed with close to 59A; sutures, close to 150B.

Flowers.—Quantity of flowers per flowering stem: Freely flowering; larger bulbs will produce plants with about ten flowers per flowering stem. Shape: Funnel-shaped; when fully opened, flowers flatten and reflex slightly. Diameter: About 14.5 cm. Depth (height): About 6 cm.

Perianth.—Quantity/arrangement: Six tepals per flower; tepals imbricate. Tepal length, inner tepals: About 8 cm. Tepal width, inner tepals: About 4 cm. Tepal length, outer tepals: About 10.4 cm. Tepal width, outer tepals: About 3.2 cm. Tepal shape: Lanceolate. Tepal apex: Acute. Tepal margin: Entire. Tepal texture, upper and lower surfaces: Smooth, glabrous. Tepal color: When opening, upper surface: Close to 25A; speckling towards the base, close to 59A. When opening, lower surface: Close to 59A. Fully opened, upper surface: Close to 25B; speckling towards the base, close to 59A. Fully opened, lower surface: Close to 25B.

Pedicels.—Angle: About 45° to 70° from vertical. Strength: Strong. Length: About 6 cm. Diameter: About 1 cm. Texture: Smooth, glabrous. Color: Close to 143B.

Reproductive organs.—Stamens: Quantity per flower: About six. Filament length: About 5.5 cm. Filament color: Close to 28C. Anther length: About 1.1 cm. Anther color: Close to 32A. Pollen color: Close to 32A. Pistils: Quantity per flower: One. Style length: About 6.5 cm. Style color: Close to 28C. Stigma length: About 5 mm. Stigma color: Close to 25B.

Fruits.—Length: About 2 cm. Diameter: About 5 mm. Color: Close to 145B.

Seed produced.—No viable seeds observed.

Disease/pest resistance.—Resistance to pathogens and pests common to Asiatic Hybrid Lilies has not been observed.

Garden performance.—Plants of the new Asiatic Hybrid Lily have exhibited good tolerance to rain and wind and have been observed to tolerate temperatures from about -15° C. to about 40° C.

It is claimed:

1. A new and distinct Lily plant named 'Tiny Orange Sensation' as illustrated and described.
